SEAL HANGER FOR FLOATING ROOF TANKS

Frederick D. Moyer, Chicago, Ill., assignor to Chicago Bridge & Iron Company, a corporation of Illinois

Application August 24, 1951, Serial No. 243,413

1 Claim. (Cl. 220—26)

This invention relates to a liquid storage tank, and more particularly to a new and improved shoe supporting means for use in conjunction with a floating roof in a liquid storage tank.

Liquid storage tanks having a floating roof therein are in wide use. Generally the roof is of slightly smaller diameter than the tank, leaving an annular space about the roof. This space is sealed by a flexible seal extending between the roof and a sealing ring. The sealing ring is generally a metal member made of one or more shoes each in sliding contact with the side walls of the tank. Many devices have been proposed for supporting the shoes of the sealing ring against the side walls, however many have been cumbersome and complicated in nature while others have not given the simplicity of operation desired.

The present invention is concerned with a new seal hanger having in a single unit means for supporting the shoes and incorporated or separate means for centering the roof within the tank. In accomplishing this result the hanger also supports the shoes without vertical movement relative to the roof. One of the principal features of the hanger is that it permits the roof to rest on the bottom of the tank in its lowermost position and to float higher in the tank so as to utilize more tank capacity.

The invention will be described with reference to an embodiment illustrated in the accompanying drawings in which Fig. 1 is a broken vertical sectional view through the side wall of the tank showing the floating roof, a shoe of the sealing ring and one of the hangers comprising this invention. The roof as shown is floating upon the liquid stored in the tank. Fig. 2 is a fragmentary elevational section taken as indicated by line 2—2 on Fig. 1. Fig. 3 is like Fig. 1 showing a different spring arrangement, Fig. 4 is a fragmentary elevational section taken as indicated by line 4—4 on Fig. 3, Fig. 5 is like Fig. 1 showing a spring separate from the hanger, and Fig. 6 is a fragmentary sectional view taken along line 6—6 in Fig. 5.

The drawings illustrate a storage tank having a bottom 10 and side walls 11 secured together in a manner to contain a stored liquid 12. A floating roof 13 having an upper deck 14 and a lower deck 15 is shown floating in the stored liquid 12. The decks are joined at the periphery of the roof by a substantially vertically positioned rim 16 secured in liquid-tight relation to both of the decks. A sealing ring 17 extends around the floating roof and comprises shoes 18 in sliding contact with the side walls 11 of the tank. The upper edges 19 of the shoes 18 are inclined inwardly in order to ride the sealing ring over any irregularities or protrusions in the tank shell 11. A flexible fabric seal 20 is secured to the edges 19 of the sealing ring and to the upper peripheral edge of the roof at 21. The space between the floating roof and the tank shell is thus sealed by the fabric 20.

The particular hanger of this invention is adapted to support the shoes 18 against the side walls of the tank and to carry the sealing ring along with the roof as it rises and falls with the liquid level within the tank. The hanger comprises a supporting bar 25 having two like portions 26 and 27 as seen in Figs. 2 and 4. It is intended that the separate bars of the supporting bar 25 act as a unit, and to this end the upper ends of the individual bars are each pivoted to a supporting bracket or lugs 28 secured to the upper portion of the

2

rim 16 of the floating roof. Individual pivot pins 29 and 30 are provided on the lugs 28 for pivotally securing the individual members of the supporting bar 25. The lower end 31 of the supporting bar is positioned adjacent to but slightly spaced from the shoe 18. The surface of the bar facing the shoe is curved as indicated at 32 so that movement of the bar about its pivot will maintain the spacing of the lower end from the shoe.

The shoes are supported and carried by the supporting bar 25 to the floating roof. To accomplish this a shoe bar 35 is pivotally connected at 36 to a lug 37 secured to the shoe. The shoe bar is an individual metallic bar which extends from its pivotal connection to the shoe downwardly in the space between the roof and shoe to the lower portion of the roof. A rod 38 is secured in the lower end of the shoe bar 35 so as to extend outwardly from either side of the bar. This rod 38 is positioned between the legs of a fixture 39 secured to the lower portion of the roof for the purpose of guiding the lower end of the shoe bar in a vertical path with respect to the roof. The fixture 39 is constructed so as to have a vertical slot 40 formed of either side of the shoe bar 35 for the reception of the rod 38. The slot 40 is of sufficient length to insure that the rod 38 will remain therein and yet not bind against the rod to limit relative movement of the roof and shoe bar.

The supporting bar and shoe bar above described are pivotally connected intermediate their ends by a pivot pin 43 extending between the members 26 and 27 of the supporting bar and through the shoe bar 35. The pin 43 is placed at substantially equal distances from the pivotal connection of each of the bars to the roof and shoe respectively. Thus the weight of the shoe is carried by the shoe bar to the pivot pin and from there to the lugs 28 secured to the floating roof. The shoes will not move vertically with respect to the roof with horizontal movement of the roof within the tank since the lower ends of both bars may move vertically without restricting the horizontal movement of the pivotal connections of the respective bars. It will be understood that the sealing ring comprising the shoes 18 is supported at intervals by hangers such as illustrated in the figures of the drawings.

It is desirable that the roof be centered within the tank. Due to wind pressure and unequal loading, however, the roof often has a tendency to move toward one portion of the side wall of the tank. In the present invention means are incorporated within the hangers to exert a force tending to center the roof within the side walls.

In Figs. 1 and 2 this force is supplied by means of a coil spring 50 wound about the pivot pin 43 securing the supporting bar to the shoe bar. The free ends 51 and 52 of the spring 50 engage the separate members 26, 27 of the supporting bar. A center portion 53 of the spring is positioned to engage the shoe bar in opposition to the force supplied by the coils of the spring to the free ends 51, 52. The coils of the spring thus supply a force which tends to bring the bars into horizontal parallelism while at the same time forcing the shoe and roof apart. The spring is so chosen that small movement of the relative positions of the ends with respect to the center portion 53 changes the force applied by the spring against the bars. Thus as the roof moves toward the side wall of the tank the spring is wound tighter, thus permitting it to exert a greater force on the bars. On the diametrically opposite side of the tank the ends and center portion of the spring on the hanger bars are moved in the opposite direction, thereby lessening the force applied by that spring against the hanger bars. This combination of increasing the force on one side of the roof, with the roof moving toward the side wall at that point, and a decreasing of the force of the spring on the opposite side of the roof provides unbalanced forces acting to return and maintain the roof centered within the tank.

In Figs. 3 and 4 of the drawings, the force for pressing the shoes against the side walls and for centering the roof within the side walls is provided by a spring 55 which is secured to a lug 56 on the rim 16 of the floating roof and a similar lug 57 secured to the lower portion of the shoe supporting bar 35. The spring 55 acts in tension

and attempts to bring the shoe supporting bar 35 and supporting bar 25 into horizontal parallelism. The action of the spring 55 is substantially the same as the coil spring 50. The hanger, by the action of the levers, supports the weight of the sealing ring regardless of the position of the ring from the roof, and the springs each acting in its own manner provide the outward push to press the sealing ring against the side wall and at the same time provide the forces necessary to center the roof within the tank.

Since the pivotal connections of the shoe supporting bar to the sealing ring and of the supporting bar 25 to the roof are in substantially the same horizontal plane, the force applied by the springs in pressing the sealing ring outwardly against the side wall is independent of any vertical force in the plane of the shoe. Thus, an increase in the vertical weight of the shoe due to friction or of freezing of moisture between the shoe and side wall will not increase or decrease or otherwise affect the outward force pushing the sealing ring against the side wall.

In the device as illustrated in Figs. 5 and 6, the force for pressing the shoes against the side walls is provided by safety pin-like springs 60 which have one leg 61 pivotally secured to the rim 16 of the roof at 62 extending downwardly from the point of pivotal connection to the roof to a coil 63. The other leg 64 extends upwardly from the coil 63 and is biased against a hook 65 secured to the end of the mounting bar 66 which is pivotally secured to the arm 36 of the hanger. This spring has its legs 61 and 64 extended downwardly generally in a vertical radial plane between the roof and shoes and exerts an outward force against the shoe reacting against the rim of the roof to press the shoes against the side walls 11.

The hangers are generally used with a mounting bar 66 so that the hanger will support the sealing ring 18 adjacent flexures therein. In Fig. 6 these flexures are clearly shown at 67 with a mounting bracket 68 secured to the shoe adjacent the flexure. The arm 35 of the hanger is secured by means of a clevis 69 to the center of the mounting bar 66, and in all other respects operates in the same manner as described with relation to Figs. 1-4. Ordinarily a spring 60 will be secured to each end of the mounting bar 66 so that two springs will be used with each hanger.

In the operation of the embodiment of Figs. 5 and 6, the hanger serves to support the shoes with relation to the roof and the springs act independently of the shoes to press the sealing ring against the side walls. As the roof moves toward the side walls, the force applied by the springs 60 increases, thereby providing a centering action or force to maintain the roof in a generally concentric position within the side walls of the tank. By removing the fabric seal 20 the springs 60 and hanger may be independently removed and replaced.

An important feature of this invention is the provision of a hanger which permits the floating roof to rest in its lowermost position on the bottom of the tank. This is possible since both the supporting bar and the shoe bar are positioned entirely within the space between the peripheral rim of the roof and the side wall of the tank.

At the same time the hanger may be completely beneath the seal fabric 20 and is thus out of contact with the elements. Also important is the fact that the hanger not only supports the shoes but maintains a pressure forcing the shoe tightly against the side walls of the tank. This is accomplished without permitting relative vertical movement of the shoes with respect to the roof. The lower ends 31 of the supporting bar previously mentioned are maintained a short distance from the shoe and will contact the shoe to limit its movement outwardly from the side wall. As the shoe moves over any irregularities or protuberances in the side wall, it will sometimes tip; and in such cases the shoe may contact the lower ends 31. When the roof is in its uppermost position with the tank substantially full of liquid, the shoes may project above the side wall of the tank in which case the lower ends 31 of the supporting bars prevent the shoes from tipping substantially out of vertical position.

While we have shown and described our invention in its preferred embodiment, it is to be understood that it is capable of many modifications. Changes, therefore, in the construction and arrangement may be made without departing from the spirit and scope of the invention as disclosed in the appended claim.

I claim:

In a liquid storage tank having a floating roof and one or more shoes adapted to slidably contact the inner side walls of the tank, means for supporting the shoes against the side walls including a supporting bar pivotally attached to the roof and extending downwardly in the space between the roof and the tank from the point of attachment to the roof to adjacent said shoe, a shoe bar pivotally attached to the shoe at one end in substantially the same horizontal plane as the point of connection of said supporting bar to the roof, said shoe bar extending downwardly from the shoe connection and connected at the other end to the roof, said connection to the roof permitting vertical movement and preventing horizontal movement of said other end with respect to the roof, a pivot pin swingably connecting said supporting bar and shoe bar intermediate their respective ends and a tension spring extending upright along the side of the roof having one end secured to the roof and the other end secured to the lower portion of the shoe bar, said spring exerting a force on said bars tending to move said roof and shoe away from each other.
